(57) **CLAIM**

The ornamental design for a glass picture frame with gemstones, as shown and described.

DESCRIPTION

FIG. 1 is a perspective front view of a glass picture frame with gemstones;

FIG. 2 is a front elevation view thereof;

FIG. 3 is a rear elevation view thereof;

FIG. 4 is a right elevation view, a left elevation view a mirror image thereof; and,

FIG. 5 is a top elevation view, a bottom elevation view a mirror image thereof.

The broken lines shown in the figures are included for the purpose of illustrating portions of the glass picture frame with gemstones that form no part of the claimed design.
